MEANS FOR OPERATING SUCTION ACTUATED DEVICES OF AUTOMOTIVE VEHICLES

Original application filed June 16, 1925, Serial No. 37,407, now Patent No. 1,753,167, dated April 1, 1930.
Divided and this application filed September 18, 1926. Serial No. 136,226.

Our invention consists in the novel features hereinafter described, reference being had to the accompanying drawings, which illustrate several embodiments of the same selected by us for purposes of illustration, and the said invention is fully disclosed in the following description and claims.

This application is a division of our former application for Letters Patent of the United States filed June 16, 1925, and given Serial No. 37,407 now Patent No. 1,753,167 Apr. 1, 1930.

In the operation of vacuum brakes or other suction actuated devices in connection with automotive vehicles where the suction actuated device is connected with the intake manifold of the engine, the air exhausted from the suction actuating mechanism and delivered into the intake manifold has a tendency to reduce the degree of rarification therein, and to prevent the drawing in of the proper quantity of liquid fuel from the carburetor, or to dilute the explosive mixture frequently to such an extent that it will not readily ignite. In either case the engine, if idling, is likely to stall, and the starting of the engine would also be materially delayed, and the operation under the control of its throttle valve would be interfered with to a greater or less extent.

In our former application for Letters Patent of the United States filed February 26, 1925, and given Serial No. 11,683, we have set forth a method of an apparatus for operating these and other difficulties by supplying motor fuel to the air exhaust from the suction actuated device before it reaches the intake manifold, so that it will enter the manifold as an explosive mixture which will combine with the explosive charges delivered into the manifold from the carburetor.

In our former application above referred to Serial No. 37,407, of which this application is a division, we have set forth means for collecting liquid hydro-carbon or motor fuel from the mixture passing through the suction passage of the engine and holding it in a capillary retaining means permeable by the air withdrawn from a suction actuated device, (as the power actuator for operat-

ing the brake mechanism of an automotive vehicle) on its way to the intake manifold to insure the proper carburetion of the air before it reaches the manifold, and have therein claimed specifically certain means for accomplishing this result.

Our present invention consists in other specific means for collecting liquid fuel from the mixture passing through the suction passage of the engine from the carburetor, and holding it in capillary retaining means located in the path of the air withdrawn from the suction actuated device, for the purpose of carbureting the said air and delivering it into the intake manifold in the form of a combustible mixture, for the purpose of preventing any material interference with the operation of the engine under the control of its throttle valve, or the stalling of the engine, if idling.

In the accompanying drawings, Fig. 1 is a diagrammatic view showing an installation in an automotive vehicle comprising an internal combustion engine, brake mechanism for the vehicle, and suction or vacuum actuated mechanism for the brake mechanism, and having our present invention embodied therein.

Fig. 2 is an enlarged sectional view of one form of power actuator which may be conveniently employed in an installation of this kind.

Fig. 3 is an enlarged view of certain parts illustrated in Fig. 1, showing the intake manifold and carburetor, the connection leading from the actuator, and the means for carbureting the air withdrawn from the actuator.

Fig. 4 is a vertical sectional view of the carbureting device shown in Figs. 1 and 3, the adjacent portions of the pipe or passage connecting the carburetor and manifold.

Fig. 5 is an enlarged view of a portion of Fig. 4.

Fig. 6 is a view similar to Fig. 5 showing a slight modification.

Fig. 7 is an enlarged sectional view of a portion of Fig. 6.

Fig. 8 is a view similar to Fig. 4 showing another slight modification.

Fig. 9 is a partial horizontal sectional view of the line 9—9 of Fig. 8.

In Fig. 1, we have shown our invention applied in connection with an automotive vehicle propelled by an internal combustion engine, and having a vacuum or suction operated actuator for operating the brake mechanism of the vehicle. In this figure, 1, represents the cylinder of a power actuator of the kind illustrated, for example, in our former applications for Letters Patent of the United States above referred to. The cylinder is provided with a double acting piston, 3, having a hollow piston rod, 5, connected by a link, 73, to a brake lever, 72, for operating the form of brake mechanism diagrammatically indicated in Fig. 1, and comprising in this instance a brake band, 71, and brake drum, 70, so that the movement of the piston applies the brakes, and in the opposite direction, releases the brakes. The actuator is provided with suitable reversing valve mechanism, in this instance located in the hub of the piston, and indicated as a whole at 6, the valve mechanism being operated by means of a valve actuating sleeve, indicated at 20, connected by a suitable link with the usual brake operating lever, 74, provided with a retracting spring, 75. As the specific form of valve mechanism has no bearing on our present invention, it will not be described in detail. 326 represents a suction pipe having a flexible portion, which is connected at one end with the valve actuating sleeve, 20, and communicates therewith, and at the other end is connected with the suction passage of the engine 60 between the throttle valve, 369, and the cylinders. 366 represents the carburetor, communicating with the manifold by a vertical pipe, 366^a. The valve actuating sleeve, 20, communicates with a suction chamber, 17, in the interior of the piston hub, which can be placed in communication with the cylinder on either side of the piston by means of suitable ports controlled by the reversing valve mechanism. The piston hub is also provided with an inlet chamber, 18, for higher pressure fluid, as atmospheric air, which chamber is in communication through the sleeve, 20, and hollow piston rod, with an inlet aperture, 5^a, formed in the latter. The valve sleeve, 20, is provided with a plug or partition, indicated at 21, separating the air inlet passage to the chamber, 18, from the suction passage to the suction chamber, 17. It will be understood that in the operation of the actuator, a forward movement of the sleeve, 20, in the direction of the arrow in Fig. 2, will admit air into the cylinder in rear of the piston, the forward portion of the cylinder being connected with the intake manifold by the suction pipe, 326, thereby causing the forward movement of the piston, while the movement of the sleeve, 20, in the opposite direction, will reverse the

connections with the cylinder, withdrawing the air previously admitted in rear of the piston, from the suction chamber, 17, and suction pipe, 326, and delivering it into the manifold, air at atmospheric pressure being admitted to the cylinder forward of the piston, and thus effecting its return movement. 70

In carrying out our present invention, we interpose between the carburetor and the intake manifold a capillary retaining means generally indicated at 61^a in Fig. 1, for holding liquid fuel obtained from the suction passage, in finely divided condition, and in such manner that the air drawn from the actuator must pass through and around said capillary retaining means and in direct contact with the liquid fuel, so as to take up the liquid fuel and form an explosive mixture before it enters the manifold. As shown in the drawings, we conveniently form this device as a ring which can be inserted in the pipe or passage connecting the main carburetor with the manifold. In these figures the manifold is connected with the main carburetor by a vertical pipe preferably formed in two parts, 366^a and 366^b, between which is located a ring, 381, provided with an annular channel, 382, open at the inner face of the ring, exterior to which channel is a second annular channel cored in the ring and indicated at 383, which communicates with the first mentioned channel at intervals by air apertures, 384, 384. The section, 366^a, of the vertical pipe or passage is provided with the usual throttle valve, indicated at 369. The inner face of the ring above and below the annular channel, 382, is provided with grooved portions, indicated at 385, and we prefer to cover the inner face of this ring with a wicking of fibrous absorbent material, easily permeable by air, as for example, a woven fabric of asbestos or other suitable material, indicated at 386. In order to hold this fibrous material in position, and also to prevent any of the particles or loose fibres thereof from passing to the engine, we prefer to place over the fibrous absorbent material, an annular piece of wire gauze, indicated at 387, said gauze and fibrous material being held in position by spring rings, 388, which press the same into the annular grooves, 385. The ring is provided with a nipple, 389, to which the suction pipe, 326, preferably a flexible pipe of rubber or other suitable material, is connected, said nipple communicating with the exterior annular recess, 383, of the ring. This ring, 381, can be readily inserted between the sections of the intake pipe leading to the manifold and secured in position by means of suitable bolts or screws, as indicated at 390, in Fig. 3, passing through lugs or ears, formed on said pipe sections, and the ring, 381, and provided with registering apertures. The annular channel, 382, is preferably provided with a depressed 130

portion, indicated at 391, below the lower lip, 391^a, of the ring, which forms an annular reservoir for the collection and retention of liquid motor fuel, and we prefer to provide the fibrous absorbent material, 386, with capillary tails, indicated at 392, which may be threads drawn out of the material or stitched into the same, or any other form of capillary appendages may be employed. These tails, 392, have their outer ends extending into the reservoir, 391, formed in the ring.

It will be understood that in this form of our invention, the absorbent material, 386, will receive and absorb liquid motor fuel from the mixture passing upward from the main carburetor to the manifold, or which may be deposited on the walls of the vertical passage and trickle downward along the walls thereof. Any excess liquid received by the absorbent material will be conducted by the absorbent tails, 392, to and be retained in the reservoir or pocket, 391, formed in the ring, and by means of these absorbent tails, there will be a more or less constant transfer of motor fuel from the said reservoir to the absorbent material, and vice versa, so as to maintain the absorbent material, 386, at all times in a moist condition. When the brake mechanism or other vacuum actuated mechanism is operated so as to withdraw air from the actuator and deliver it into the annular passage, 383, on its way to the manifold, such air will be distributed through the passages, 384, to the channel, 382, of the ring, and will thence pass through the capillary or absorbent material, 386, before it enters the vertical passage connecting the main carburetor to the manifold, which insures the proper mixture of motor fuel with said air to form a combustible mixture which mixes with the charge forming mixture passing from the carburetor.

In Figs. 6 and 7, we have illustrated a slight modification of the ring shown in Figs. 3, 4 and 5. In this construction the ring, indicated at 481 is provided with the inner channel, 482, open to the vertical pipe or passage, the sections of which are indicated at 466^a and 466^b, said ring being provided also with the exterior annular channel, 483, communicating by apertures, 484, with the inner channel, 482. The inner and upper edge of the channel, 482, is carried inwardly to produce an annular flange, 485, which projects into the vertical passages, so as to deflect portions of the charge forming mixture drawn upward from the main carburetor, into the interior channel, 482, to cause it to deposit a portion of its liquid fuel, and said channel, is provided with absorbent material to retain the same, which may be in this instance conveniently provided in the form of a ring, 486, of asbestos or other absorbent material, protected by an exterior coating of wire gauze, 487, and conveniently

provided with an interior stiffening wire, 488, said ring being sufficiently flexible to be sprung into its place in the channel, 482. The ring is provided with the nipple, 489, connected with the suction pipe, 426, and the operation of the device is practically the same as that previously described. It will be seen that the air entering from the suction pipe, 426, will be distributed through the small apertures, 484, into the inner channel, 482, directly in contact with the moist capillary material supported therein. The lower portion of the channel, 482, also forms a reservoir, indicated at 491, the inner lower edge of said channel being provided with an upwardly extending lip, 491^a, as shown.

In Figs. 8 and 9 we have shown another slight modification of the ring and the capillary material carried thereby. In this instance the sections of the vertical passage are indicated at 566^a and 566^b, and the ring itself is indicated at 581, being conveniently formed in two sections for convenience of manufacture. 582 represents the inner channel, and 583, the exterior channel, communicating with the inner channel by apertures, 584, which are located adjacent to the bottom of the channel, 582, and said channel is provided with a lip, 591^a, at its lower edge, forming a liquid reservoir, 591, and with a downwardly extending lip, 585, at its upper edge. Within the channel is provided an annular ring, 586, of capillary material, such as an absorbent mass of fibrous material pressed into form, for example, asbestos, and which may be protected by a covering of wire gauze or other material as desired, the said ring being provided on its inner edge with radially disposed projections, or tongues, 586^a, which project over the lip, 591^a, toward the interior of the vertical passage from the main carburetor. In this instance the inwardly projecting tongues, or fingers, 586^a, thus serve to collect liquid motor fuel from the charge forming mixture passing upwardly from the main carburetor, and by capillary action, transmit it to the main body of the ring, 586, and to the reservoir, 591, in the manner hereinbefore described, the said ring being provided with depending portions, 586^b, or capillary tails to insure the transfer of liquid to and through said reservoir. The air entering from the suction actuated device through the pipe, 526, passes through the small apertures, 584, into said reservoir, 591, and through the absorbent material of the ring, 586, becoming admixed with motor fuel and entering the passage, as explosive mixture to be mixed with the charge forming mixture, as hereinbefore described.

It will be understood that in all of the forms of our invention, we prefer to connect the suction pipe to the suction passage of the engine between the throttle valve and the cylinders.

What we claim and desire to secure by Letters Patent is:—

1. Means for fuelizing air withdrawn from a suction actuated device deriving its suction from the suction passage of an internal combustion engine, comprising a ring inserted between and joining the sections of said suction passage and forming a part of said suction passage, said ring provided with an annular chamber communicating at all times with said suction passage, said ring being provided with a liquid reservoir in the bottom of the chamber, a capillary medium exposed to contact with motor fuel passing through said suction passage and having portions extending into said reservoir, and a suction connection between said device and said chamber whereby all air withdrawn from said device will contact with the capillary medium and be fuelized.
2. Means for fuelizing air withdrawn from a suction actuated device deriving its suction from the suction passage of an internal combustion engine, comprising a ring inserted between and joining the sections of said suction passage and forming a part of said suction passage, said ring provided with an annular chamber communicating at all times with said suction passage, said annular chamber being provided at its bottom with a liquid reservoir, a capillary medium bridged across the communicating opening between said chamber and the suction passage and having capillary extensions dipping into said reservoir, and a suction connection between said device and said chamber whereby all air withdrawn from said device will contact with the capillary medium and be fuelized.
3. Means for fuelizing air withdrawn from an intermittently operated suction actuated device deriving its suction from the suction passage of an internal combustion engine, comprising means arranged within the suction connection and forming a part thereof, said means having an annular chamber communicating with the suction passage, a capillary medium bridged across the communicating opening and subjected to contact with the motor fuel passing through said suction passage, means connected to said capillary medium for delivering excess motor fuel to said chamber, and a suction connection from said chamber to said device, whereby all air withdrawn from the suction actuated device will contact with said capillary medium and be fuelized before entering the suction passage.

In testimony whereof we affix our signatures.

CALEB S. BRAGG.
VICTOR W. KLIERSRATH.
